[57] ABSTRACT

It has been found that successive tin and gold deposits upon tin-receptive substrates, in combined deposit thicknesses under 100 microinches, have certain synergistic properties which are highly useful in the electrical arts. Although tin and gold deposits per se are highly porous, even in individual deposit thicknesses of 100 microinches, upon appropriately selected and prepared substrates composite deposits of selected thickness are found to have virtually zero porosity. The composite deposits have other desirable properties useful in electrical device manufacture. These include prolonged resistance to wear and corrosion, good conductivity, low surface contact resistance and surface receptiveness to union with solder.

1 Claim, No Drawings

chemical reduction baths (GATC or Enthone) for 15-20 minutes at 195°F.

Method:

Deposit dull tin (15-20 microinches) upon the nickel film, rinse and deposit gold upon the tin film. These metals can if desired be deposited in a pattern via a photo resist mask. The deposition can also be of the non-electrolytic type, e.g., vacuum, sputtering, electroless, immersion, etc.

Materials and Parameters:

Same as Example 3.

Properties:

Same as Example 4.

EFFECT OF VARIATION OF TIN DEPOSIT THICKNESS

Example 1

At less than 15 microinches porosity increase noted.

Between 15 and 45 microinches porosity test continued to indicate 0 porosity. At greater than 45 microinches flaking of the gold occurred.

Example 3

Specimens were produced with tin layer thicknesses of 10, 30 and 60 microinches. All specimens exhibited substantial porosity ranging from 20-30 percent (for the 60 microinch specimen) to 100 percent (for the 10 microinch specimen).

We have shown and described above the fundamental novel features of the invention as applied to several preferred embodiments. It will be understood that various omissions, substitutions and changes in form and detail of the invention as described herein may be made by those skilled in the art without departing from the true spirit and scope of the invention. It is the intention therefore to be limited only by the scope of the following claims.

10 What is claimed is:

1. A laminate surface coating for electrical contact applications — characterized by absence of porosity and by possession of durability, resistance to corrosion and wear and low contact resistance — formed by adjacent deposits of tin and gold, in respective thickness ranges of 15-40 microinches of dull tin and about 20-35 microinches of gold, wherein said tin deposit is adhered to a substrate including at least 15 microinches of nickel at the adhesion interface with said tin deposit, and said gold deposit covers said tin deposit and forms an exposed outer surface suitable for entering into touching contact engagement with other conductor media to make and break electrical circuit connection, and the composite of said tin-gold deposits possesses the above characterized properties.
